LIQUID GAUGE TUBE

Nusyn Dobrzynski, Hadera, Palestine

Application May 19, 1942, Serial No. 443,661
In Palestine October 9, 1941

8 Claims. (Cl. 222—136)

This invention relates to volumetric pipettes generally, such as used in chemistry or bacteriology, and inter alia to mixing pipettes, that is, pipettes into which two liquids are sucked in one after the other in order to be mixed in the pipette in the desired exact proportion. This invention is especially useful in its application to the dilution of blood in connection with blood count.

The general purpose of pipettes is to allow of exact measurings of liquids as possible. With the common type of pipettes, the liquid is usually sucked in with the mouth and adjusting of its level in the pipette is done in different ways. As a rule the top end of the pipette is closed by the finger, and by gradually lifting the finger the liquid is allowed to flow out until its level reaches exactly the mark. With capillary pipettes, the adjustment of the level is obtained by slightly blowing air into the pipette and by wiping its outer end so as to suck liquid out of the latter. These methods are not expeditious and are subject to individual abilities. Therefore, the measurings are liable to be inaccurate. After the level of the liquid has been adjusted, there remains an excess drop of liquid at the outflow end of the pipette and the necessary removal of this drop draws some liquid out of the pipette which makes the measuring faulty. Besides, the operation of sucking in the liquid by the mouth has obvious drawbacks from a hygienic point of view.

It is also known to connect compressible rubber bulbs to the top of pipettes which allow of sucking the liquid into and pressing it out of the pipette by creating respectively reduced and elevated pressure within the pipette. Known arrangements of this kind, while being satisfactory from a hygienic point of view, do not add to the accuracy of the measuring.

The main object of this invention is to increase the accuracy of measurings effected by means of pipettes.

The invention consists essentially in the provision on a pipette of an obturator for closing its intake end, and of mechanical means for pressing the obturator against said intake end and gradually removing it therefrom in order to control the rate of flow of the liquid entering or leaving the pipette by the action of said reduced or elevated pressure from zero up to a full free flow. By regulating the rate of flow to a small value, a highly exact adjustment of the liquid level in the pipette to the desired mark can be obtained. Any excess of liquid left on the

obturator when the latter has again been brought into closing position can easily be washed off therefrom without thereby sucking liquid out of the intake end of the pipette.

5 As already mentioned above, the invention is particularly useful in its application to mixing pipettes for diluting blood for blood count. Different diluting ratios and diluting liquids are required for counting erythrocytes and leucocytes wherefore two different pipettes are used. Hitherto, one diluting operation has first to be completed and only then can the second one be started which makes it necessary in many cases to make a fresh prick in order to obtain a further sample of blood from the patient.

10 According to this invention, two mixing pipettes serving respectively for erythrocyte and leucocyte counting, are mounted on a common support and connected to a common rubber bulb so that a reduced or elevated pressure can be created in both of them at the same time, while each pipette has its own obturator with separate control means. The two diluting operations can be performed at the same time from 15 two samples of blood taken from the patient practically simultaneously.

An execution form of a blood diluting device is illustrated by way of example in the accompanying drawing in which:

20 Fig. 1 is a front view;

Fig. 2 a corresponding side elevation, with some parts being omitted;

Fig. 3 a rear view, partly broken away.

25 In the execution form illustrated, a pipette 1 for erythrocyte counting and a pipette 2 for leucocyte counting, with mixing bulbs 1', 2' respectively, are mounted in parallel on a plate 3 to which they are fixed by means of clamps 4. They are connected through rubber tubes 5, 5' to a T 6 fixed to plate 3 by means of a ring 7. The third branch of T 6 bears a compressible hollow rubber bulb 8. A hole 9 is provided in T 6 and this is normally closed by a shutter 10 pressed thereagainst by means of a flexion spring 11 which is fixed to the back of plate 3. A further flexion spring 12 is fixed to plate 3 in such position that it can be pressed against tube 5 whereby the latter is compressed. This is done by 30 means of a clamping screw 13.

35 Two obturators 14 are provided for the intake ends of the pipettes, one for each pipette. These obturators are mounted each on the lower end of a vertical rod 15 which can be shifted axially parallel to the axis of the pipette and be turned 40 round its own axis. From the lower end of the

rod there extends a horizontal fork over the prongs of which a broad endless rubber band is slipped, as shown in Fig. 1. This is the obturator proper which provides a good closure of the pipette with a soft pressure. The rod 15 is guided on the rear side of plate 3 in clips 16, 16' and has at its upper end a knob 17 beneath which a ring 18 is loosely seated on the rod. Two arms 19 extend laterally from the ring, and to each of them a coil spring 20 is connected which is fixed on its opposite end to plate 3. The rubber band is thus drawn up against the end of the pipette by springs 20. If now the obturator is lowered and rod 15 is turned by about 180° so as to bring the obturator away from the pipette, the rod 15 is urged upwardly and follows the traction until an abutment 21 fixed to it applies itself to the clip 16. The abutment 21 is in the form of two small arms projecting laterally from the rod. A lever 22 is articulated to plate 3 so as to rest on knob 17. This lever has a knob 23 and serves for lowering very slowly the obturator from the end of the pipette. Now, this should sometimes be carried out with the utmost care and over a very small way only, especially in the case of very fine capillary pipettes. This object can be attained by providing a further lever 24, equally articulated to plate 3 above the lever 22 and adopted to rest on a stop 25 fixed on plate 3. This lever has at its free end a threaded sleeve 26 in which a screw 27 is inserted, and by screwing this downwardly while lever 24 is at the same time pressed against stop 25, lever 22 is slowly pressed down at a very slight rate of motion, and the rubber band is accordingly very gradually removed from the pipette. A similar arrangement may be provided with the other pipette as well, but this has been omitted in the drawing for the sake of simplicity.

It is evident that by very slightly lowering the rubber band, only a very narrow slit is created between the end of the pipette and the rubber band through which slit the liquid can only very slowly enter or leave the pipette, as the case may be, which allows of a very exact and convenient adjustment of its level in the pipette or of the amount withdrawn. On the other hand, if a large amount of liquid is rapidly to be sucked in or pressed out, the obturator is fully lowered and possibly turned away.

The apparatus described by way of example is operated in the following way:

Screw 13 is tightened so as to compress the tube 5 almost entirely. One obturator is lowered and turned away from the end of its pipette, and this end is dipped in a drop of blood, such as obtained by a prick on a finger tip, whereafter screw 13 is untightened so much as to cause some blood to be sucked into that pipette and to rise therein a little above the mark provided for determining the exact amount of blood to be taken. The obturator is then put back into closing position. The same procedure is repeated with the second pipette for which the supply of blood obtained by that one prick is still sufficient. Now, both pipettes being closed and each of them containing an excess of blood screw 13 is again tightened by one turn or one turn and a half, whereby the pressure in both pipettes is raised. Now, one of the levers 22 is carefully pressed upon, which creates a narrow slit between the pipette and the rubber band through which a quantity of blood is expelled until the level of the blood in the pipette reaches exactly the mark,

and at this moment lever 22 is released. The same is then done with the second pipette.

Instead of sucking the blood from the prick, as described above, some blood can be put on both obturators at a time directly from the finger tip (which is particularly indicated where no substantial drops of blood into which the pipettes can be dipped form on the puncture) while screw 13 remains tightened, then the obturators are put back into closing positions so as to let the ends of the pipettes dip into the blood drops. When screw 13 is now untightened, the pressure lowers in both pipettes but nothing happens until by again slightly lowering the obturators the blood can be sucked in from the obturator. This is done with one pipette after the other, and by careful work it is possible to stop the inflow at the very moment when the blood has risen to the mark.

With both methods, any excess of blood to be found on the obturators is then washed off. Spring 11 is now pressed upon from the back of the apparatus so as to uncover hole 9, the bulb 8 is compressed and the spring and bulb are then released one after the other so that the bulb is now evacuated. Finally, the ends of the pipettes are dipped into the diluting liquids, one obturator after the other is again carefully lowered by means of the corresponding lever and the respective liquid is sucked into each pipette up to the provided mark. This is best done with both pipettes simultaneously by means of a vessel divided into two compartments each of them containing one of the diluting liquids, so that both pipettes are dipped in their corresponding liquids at the same time. Hole 9 is again uncovered for a moment in order to restore atmospheric pressure in the pipettes. The diluting liquids are then mixed with the blood in each pipette by shaking the apparatus, the portions of liquid contained in the lower ends of the pipettes beneath the mixing bulbs proper are rejected, and the desired quantity of diluted blood is withdrawn from each pipette and put in a counting chamber. Bulb 8 can be removed from T 6 for cleansing and drying the pipettes.

The invention can be applied also to other liquid gauge tubes, such as burettes.

I claim:

50. 1. Device for the accurate measuring of liquids, comprising in combination, a liquid gauge tube, a shift rod adapted to move parallel to the axis of said tube exteriorly of said tube and to be turned about its own axis, an obturator including a piece of resilient material mounted on the bottom end of said rod, at least one spring serving to press said obturator against the bottom end of said tube for closing its opening, and a lever adapted to press on said rod for shifting the rod against the action of said spring for the purpose of controlling the rate of flow of liquid through said end of the tube.
55. 2. Device for the accurate measuring of liquids, comprising in combination, a liquid gauge tube, an attached device connected to the upper end of said tube and adapted to alternately create elevated, atmospheric and reduced pressure in said tube, an obturator including a piece of resilient material disposed beneath the bottom end of said tube, and mechanical means serving to press said obturator against said bottom end for closing its opening, and allowing said obturator to be moved gradually towards and away from said end for controlling the rate of flow of liquid therethrough.
60. 3. Device for the accurate measuring of liquids, comprising in combination, a liquid gauge tube, an attached device connected to the upper end of said tube and adapted to alternately create elevated, atmospheric and reduced pressure in said tube, an obturator including a piece of resilient material disposed beneath the bottom end of said tube, and mechanical means serving to press said obturator against said bottom end for closing its opening, and allowing said obturator to be moved gradually towards and away from said end for controlling the rate of flow of liquid therethrough.
65. 4. Device for the accurate measuring of liquids, comprising in combination, a liquid gauge tube, an attached device connected to the upper end of said tube and adapted to alternately create elevated, atmospheric and reduced pressure in said tube, an obturator including a piece of resilient material disposed beneath the bottom end of said tube, and mechanical means serving to press said obturator against said bottom end for closing its opening, and allowing said obturator to be moved gradually towards and away from said end for controlling the rate of flow of liquid therethrough.
70. 5. Device for the accurate measuring of liquids, comprising in combination, a liquid gauge tube, an attached device connected to the upper end of said tube and adapted to alternately create elevated, atmospheric and reduced pressure in said tube, an obturator including a piece of resilient material disposed beneath the bottom end of said tube, and mechanical means serving to press said obturator against said bottom end for closing its opening, and allowing said obturator to be moved gradually towards and away from said end for controlling the rate of flow of liquid therethrough.
75. 6. Device for the accurate measuring of liquids, comprising in combination, a liquid gauge tube, an attached device connected to the upper end of said tube and adapted to alternately create elevated, atmospheric and reduced pressure in said tube, an obturator including a piece of resilient material disposed beneath the bottom end of said tube, and mechanical means serving to press said obturator against said bottom end for closing its opening, and allowing said obturator to be moved gradually towards and away from said end for controlling the rate of flow of liquid therethrough.

3. Device for the accurate measuring of liquids, comprising in combination a liquid gauge tube, an elastic bulb and connecting means including an elastic tube connecting said bulb to the upper end of said gauge tube, mechanical means serving to compress said elastic tube to any desired degree, an obturator including a piece of resilient material disposed beneath the bottom end of said gauge tube, and mechanical means serving to press said obturator against the bottom end of the gauge tube for closing its opening, and allowing it to be moved gradually towards and away from said end for controlling the rate of flow of liquid therethrough.

4. Device for the accurate measuring of liquids according to claim 3, having an air communication port in the means connecting the bulb to the upper end of the gauge tube, closing means in conjunction with said air communication port, and a spring serving to press said closing means on said air communication port.

5. Device for the accurate measuring of liquids, comprising in combination, a liquid gauge tube, a shift rod adapted to move parallel to the axis of said tube and to be turned about its own axis, an obturator including a piece of resilient material mounted on the bottom end of said rod, at least one spring tending to press said obturator on the bottom end of said gauge tube for closing its opening, a lever serving to press on said rod for shifting the rod against the action of said spring to control the rate of flow of liquid through said end of the tube, a support on which said lever is mounted and to which said spring is connected, a sleeve with an inner thread mounted on said support, an adjusting screw inserted in said sleeve and adapted to be applied against said lever for pressing it on the said rod, an elastic bulb, and connecting means including an elastic tube connecting said bulb to the upper end of said gauge tube, an air communication port in said connecting means, closing means associated in conjunction with said air communication port, and a spring tending to press said closing means on said air communication port.

6. Device according to claim 5, comprising an abutment provided on the support above said lever, a further lever swingingly mounted on said support and adapted to be applied against said

abutment, the said threaded sleeve being carried on the free end of said second lever.

7. Device for measuring and diluting blood for blood count, comprising in combination, two mixing pipettes arranged in parallel, a common support carrying said pipettes, two obturators each including a piece of resilient material individually disposed beneath the bottom end of each pipette, mechanical means serving to separately press each obturator against said ends of the pipettes for closing their openings and allowing the obturators separately to be moved gradually towards and away from said ends for controlling the rate of flow of liquid therethrough, and a common attached device connected to the upper ends of said pipettes and adapted to alternately create elevated, atmospheric and reduced pressure in said pipettes.

8. Device for measuring and diluting blood for blood count, comprising in combination, two mixing pipettes arranged in parallel, a common support carrying said pipettes, two shift rods, one in conjunction with each pipette, said rods being guided on said support parallel to said pipettes and adapted each to be turned about its own axis, obturators comprising each a piece of a resilient material, each mounted on the bottom end of one rod, springs adapted to press each obturator separately against the bottom end of its pipette, two swinging levers in conjunction with said rods, said levers being swingingly mounted on said support and adapted separately to press on the top ends of said rods and to shift the rods against the action of said springs, and allowing separately to move said obturators towards and away from said ends of the pipettes for controlling the rate of flow of liquid therethrough, a T with three branches mounted on said support, elastic tubes connecting the top ends of said pipettes respectively to two branches of said T, clamping means adapted to compress one of said elastic tubes to any desired degree, an elastic bulb connected to the third branch of said T, an air communication port in said T, a shutter adapted to close said air communication port, and a spring adapted to press said shutter on said port.

NUSYN DOBRZYNISKI.
